CIGARETTE HOLDER

Charles E. Wheelock, Syracuse, N. Y.

Application June 20, 1950, Serial No. 169,122

1 Claim. (Cl. 131—175)

1
This invention relates to improvements in smokers' articles.

An object of this invention is to provide a safety device adapted to be used in combination with a standard cigarette holder or a substantially standard cigarette holder to cover the cigarette whereby persons, for example, patients in hospitals, convalescent homes, etc., may smoke safely in bed, whereby a lighted cigarette may be rested upon an article as a table or a bed without burning the same.

Other objects and features of importance will become apparent in following the description of the illustrated form of the invention.

In the drawings:

Figure 1 is a perspective view of the device;
Figure 2 is a longitudinal sectional view of the device in Figure 1;

Figure 3 is an elevational view of the device with the closure in the open condition;

Figure 4 is a transverse view taken substantially on the line 4—4 of Figure 2 and in the direction of the arrows;

Figure 5 is a sectional view taken substantially on the line 5—5 of Figure 2 and in the direction of the arrows; and

Figure 6 is an end view of the device with the cigarette holder omitted.

In carrying out this invention, there is provided a cigarette holder 10 comprising a stem 11 having a smoke passage 13 terminating at its outer end in a bore or enlargement 12 adapted to accommodate a cigarette. This cigarette holder 10 further includes a reduced outer end portion 15 which provides a shoulder 14 to act as an abutment.

A casing 17 is removably mounted on the holder 10. The casing 17 includes, on its inner end, a ring 24 which frictionally receives the end portion 15 of the holder 10 and abuts the shoulder 14. Projecting outwardly from the ring 24 is a substantially U-shaped integral trough 16 comprising an outer end wall 20. The end wall 20 rises above the trough 16 and the upper portion thereof is rabbetted in a manner to provide a seat 22.

The casing 17 further comprises a swinging closure 28 for the opening 18 of the trough 16. The closure 28 is substantially U-shaped in transverse section and the inner end thereof is pivotally secured to the ring 24 by pins 32 and 34. The outer or free end of the closure 28 is engageable on the seat 22. When in closed position, the longitudinal marginal portions of the closure 28 overlap the corresponding portions of

the trough 16 as shown to advantage in Figure 4 of the drawing.

Formed integrally with the pivoted end of the closure 28 is an inwardly and upwardly inclined operating tongue 30. Mounted on the inner end of the casing 17 is a substantially U-shaped spring 36. The spring 36 comprises angular legs 40 and 42 having their free end portions embedded longitudinally in the ring 24. Interposed in the legs 40 and 42 at the angles thereof are coils 41. The bight portion 43 of the spring 36 is engaged under tension with the inner face of the tongue 30 for yieldingly urging the closure 28 toward closed position.

15 In operation, the standard cigarette holder 10 is provided with a cigarette. Then the cigarette and the end of the holder which has the cigarette therein is inserted in the ring 24 of the casing 17. The cigarette may then be lighted, or, more practically, the cigarette may first be lighted.

Thereafter, when the person desires to smoke the cigarette, the closure 28 is held open by the individual's finger to provide sufficient air for 25 proper burning. As soon as the person is finished smoking (temporarily), the closure is permitted to be closed by the spring 36.

In the event that the person inadvertently, as by falling asleep, allows the device with a burning cigarette therein to fall, the closure 28 will 30 automatically close, thereby preventing fire. The device may be used as a matter of convenience for temporarily resting the cigarette on any article without burning that article or causing a fire.

35 Having described the invention, what is claimed as new is:

A cigarette holder comprising a stem having a longitudinal smoke passage therein, said smoke 40 passage including an enlarged outer end portion for the reception of a cigarette, said stem further including an externally reduced outer end portion providing a shoulder, a removable casing on the stem including a ring encircling the reduced end portion of said stem in abutting 45 engagement with the shoulder, an integral trough of substantially U-shaped cross section projecting longitudinally from the ring, an integral, up-standing end wall on the trough including an enlarged upper portion having a rabbetted edge portion providing a seat, a closure of substantially U-shaped transverse section having one end pivotally secured to the ring for vertical swinging movement and adapted to close the 50 trough with its longitudinal marginal portions

overlapping the corresponding portions of said trough, the free end of said closure being engageable on the seat, an inwardly and upwardly inclined tongue integral with the inner end of the closure, and a substantially U-shaped spring for yieldingly urging the closure toward closed position, said spring comprising legs including coils at an intermediate point, the end portions of said legs being embedded longitudinally in the ring, the bight portion of said spring 10 being engaged beneath the tongue.
